UNITED STATES PATENT OFFICE

2,185,927

INSUFFLATOR

Herman A. Shelanski, Philadelphia, Pa.

Application February 16, 1937, Serial No. 126,094

3 Claims. (Cl. 128—266)

This invention relates to vaginal insufflators, and the object of the invention is to provide a highly efficient and extremely simplified device for inflating the vagina to an extent whereby 5 folds in the walls thereof will be straightened out; and whereby a medicament in the form of a finely divided powder will be injected into the extended vaginal cavity in the form of a cloud and which will, by proper manipulation of the 10 device, be caused to settle on all parts of the smoothed walls and on the external surfaces of the patient's anatomy immediately surrounding the vaginal orifice.

Another object of the invention is to provide 15 the device with an insufflating nozzle and seal which may be readily detached for sterilizing after each treatment.

Another object of the invention is to provide 20 an insufflating nozzle devoid of small openings which in devices in common use at the present time too frequently become clogged by secretions while inserting the device preliminary to treatment and by which the powder is prevented from being evenly dusted onto and uniformly distributed 25 over the walls of the vagina.

Another object of the invention is to provide 30 a device which can be readily applied to containers in which the powder is originally packed for distribution, thus eliminating loss and inconvenience attending the filling of a receptacle 35 forming part of the device from an original package.

Other objects and features of the invention 40 will become apparent from the following description of the construction and operation of the device when taken with the accompanying drawing, of which:

Fig. 1 is a longitudinal vertical section of the 45 device attached to an original package of medicament;

Fig. 2 is a plan view; and

Fig. 3 is a transverse section taken on the line 3—3, Fig. 2.

As shown in Fig. 1, an original package of 45 medicament in finely divided powdered form is shown as a glass or other jar, bottle or vial 1, and which has a wide mouth or neck 2 in the present instance provided with external screw threads 3.

The device proper includes a cap 5 for the bottom 50 1 and which may be made of a suitable non-corrosive material, metal, hard rubber, Bakelite, etc. The cap 5 is internally threaded, as indicated at 4, for engagement with the threads 3 on the bottle 1. The cap 5 carries a resilient

washer 6 which is adapted to be drawn down tightly against the open end of the bottle 1 to make an air-tight seal between the bottle 1 and cap 5.

The cap 5 is provided with a head 7 from 5 which extends in opposite directions, in the present instance, a pair of axially aligned projections 8 and 9.

The projection 8 is shaped in a well known manner to fit within one end of a tube 10. The 10 opposite end of the tube 10 is attached to a hand bulb 11, in the present instance, although it will be understood that the second end of the tube 10 may be connected to any desired or available 15 source of air under pressure or means for producing an air or other gaseous pressure in the tube 10.

The tube-receiving projection 8 is axially bored 20 at 12 from its outer end inwardly to substantially the axis of the cap 5 where said bore 12 intersects a bore 13 which extends parallel to and closely adjacent the axis of the cap 5.

Secured in the bore 13 and projecting from the cap 5 into the bottle 1 to a plane substantially midway between the closed bottom and 25 open top end of the bottle 1 is a tube 14 which may be of non-corrosive metal, hard rubber, Bakelite, etc. and which is open at its lower or projecting end 15.

The second projection 9 on the cap 5 is threaded 30 at 16 to receive a readily detachable nozzle 17 whereby said nozzle may be conveniently detached for sterilizing.

The projection 9 and nozzle 17 are axially bored at 18 and 19 respectively to a uniform diameter 35 throughout their respective lengths and in alignment one with the other.

The bore 18 in the projection 9 communicates and in the present instance intersects with a bore 20 formed in the head 7 of the cap 5 and 40 which is disposed parallel to and immediately adjacent the axis of the cap 5. The bore 20 is of equal diameter to the bore 17—18 and is preferably disposed with its axis in a common plane with the axis of the tube 14, one at one 45 side of the axis of the cap 5 and the other at the opposite side of said axis and both located as close to the axis of the cap and to each other as possible or practical from a manufacturing point of view.

The nozzle 19 is provided with a circular enlargement or collar 21, which may be formed integral with the nozzle 19 or rigidly or adjustably secured therein as indicated at 23, if desired.

The collar 21 is preferably tapered toward one 55

end and provided with a circular flange 22 adjacent its opposite end. A bell-shaped resilient cup 25 is firmly seated at its smaller end 24 on the tapered body of the collar 21 and is snugly seated against the flange 22, the outwardly flaring end 23 projecting backwardly over the nozzle 19 toward the bottle 1 or cap 5.

The bell-shaped cup 25 is of such proportions or made in a variety of sizes that its external surface will fit snugly within the external orifice of the vaginal cavity to seal the same against ingress and egress of air, etc. to and from the interior of the vagina during the insufflating operations.

15 The single bore 19 of the nozzle 17 is of such a diameter that it will not become clogged by secretions during the inserting thereof or subsequently and which will conduct the finely divided powder while in suspension in air or other gaseous vehicle to the extreme end 30 of the nozzle at which the powder will emerge from the nozzle in the form of a cloud.

20 The powder propelled by the gaseous vehicle will be carried into contact with the walls of the 25 vagina which have been ballooned or smoothened or straightened out by pressure built up within the vagina, sealed by the guard 25 by the pressure of the gaseous vehicle supplied through the nozzle 17.

25 The gaseous vehicle is supplied through the bore 12 of the cap 5 and enters the bottle 1 through the tube 14. The lower end of the tube, by being located down well in the bottle 1, causes the gaseous vehicle passing therethrough to impinge upon the powder in the bottle 1. This causes the gaseous vehicle to whirl in the bottle around the tube 14 and thereby agitate and carry along the finely divided particles of powder. The swirl of the air and powder suspended therein 30 around the tube 14 passes upwardly in the bottle 1 and enters the bore 20 in the cap 5, from which the eddy currents of gaseous medium enters the bore 18 of the projection 9 and passes into the bore 12 of the nozzle 17, from which it emerges in 35 the form of a cloud as above noted.

40 After this procedure has been followed for a desirable length of time, the nozzle is withdrawn slightly, breaking the seal produced by the guard 25. The pressure in the ballooned vagina thereby 45 is permitted to escape around the rim of the guard 25 and in so doing the cloud of medicated powder is caused to settle on the surfaces, etc. immediately surrounding the external orifice of the vagina.

50 55 After the treatment is completed, the nozzle 17 may be readily removed from the cap 5 by unscrewing at 18 and the guard 25 may be readily slipped off the nozzle 17 so that they may be separately sterilized when desired.

60 65 While the device above described is made primarily for the treatment of humans, it may be produced in various sizes for the treatment of animals from the smallest to the largest.

I claim:

1. An insufflator comprising a container for finely divided powder; a cap on said container having an inlet passage therein, including a straight portion extending radially from a point near the center of the cap to the exterior surface 5 of the cap and a straight portion extending axially of said cap and having its inner end communicating with the straight portion of said inlet passage and its outer end communicating with the interior of said container, the outer end of the 10 straight portion of said inlet passage adapted for connection to a source of gaseous fluid under pressure, said cap having an outlet passage therein including a straight portion extending radially from a point near the center of the cap to the exterior surface 15 of the cap and a straight portion extending axially of said cap and having its inner end communicating with the straight portion of said outlet passage and its outer end communicating with the interior of said container; and a 20 tube connected to the outer end of the axially positioned portion of the inlet passage in the cap and extending into said container a substantial distance below said cap, whereby the gaseous fluid under pressure flows through said tube and 25 into the container to force the powder therein through the outlet passage in said cap.

2. An insufflator as defined in claim 1 and including a nozzle having a straight passage therein communicating with the outlet passage in the 30 cap, with the straight passage in the nozzle in axial alignment with the straight outer portion of the outlet passage in the cap.

3. An insufflator comprising a container for finely divided powder; a cap on said container 35 having an inlet passage therein, including a straight portion extending radially from a point near the center of the cap to the exterior surface of the cap and a straight portion extending axially of said cap and having its inner end communicating with the straight portion of said inlet passage and its outer end communicating with the interior of said container, the outer end of the straight portion of said inlet passage adapted 40 for connection to a source of gaseous fluid under pressure, said cap having an outlet passage therein including a straight portion extending radially from a point near the center of the cap to the exterior surface of the cap and a straight portion extending axially of said cap and having its inner end 45 communicating with the straight portion of said outlet passage and its outer end communicating with the interior of said container; a tube connected to the outer end of the axially positioned portion of the inlet passage in the cap and extending into said container a substantial distance below said cap; a nozzle connected to the cap and communicating with the outer end of the outlet passage in the cap; a vaginal seal adjustable along the nozzle; and means for rigidly securing said seal in a predetermined position relative to the outer end of the nozzle.

HERMAN A. SHELANSKI.
